UNITED STATES PATENT OFFICE.

PENROSE R. HOOPES, OF HARTFORD, CONNECTICUT.

DISPENSING MACHINE.

Application filed May 1, 1926. Serial No. 106,027.

My invention relates to the class of machines employed for dispensing various articles of merchandise, and an object of my invention, among others, is the production 5 of a machine of this class that shall be simple in construction and particularly efficient in operation, and one in which the loading of the machine may be easily and readily effected.

10 One form of a machine embodying my invention and in the construction and use of which the objects herein set out, as well as others, may be attained, is illustrated in the accompanying drawings, in which—

15 Figure 1 is a view in front elevation of a machine embodying my invention.

Figure 2 is a view in side elevation of the same, partially in section.

20 Figure 3 is a view in rear elevation of the upper portion of the machine with the back cover removed.

25 Figure 4 is a view, scale enlarged and in section, of the upper part of the machine on a plane denoted by the dotted lines 4—4 of Figures 1 and 5.

Figure 5 is a front view, scale enlarged, of the upper portion of the case with the upper cover and cover case removed.

30 Figure 6 is a view in section on a plane denoted by the dotted line 6—6 of Figure 4.

Figure 7 is a view in section on a plane denoted by the dotted line 7—7 of Figure 4, with parts broken off.

35 Figure 8 is a detail view illustrating the operation of the indicating device, with the parts shown in one position.

Figure 9 is a similar view showing the parts in another position.

40 Figure 10 is another view showing the parts in still another position.

Figure 11 is a view of a portion of the apparatus on a plane denoted by the dotted line 11—11 of Figure 8.

45 Figure 12 is a view of a portion of the device on a plane denoted by the dotted line 12—12 of Figure 8.

Figure 13 is a detail view illustrating the actuating mechanism for the dispensing mechanism.

50 Figure 14 is another view illustrating said mechanism, this being an isometric view looking from the back.

Figure 15 is a view similar to Figure 13, but

showing a different position of parts, Figures 13 and 15 illustrating the parts principally 55 in dotted lines.

In the accompanying drawings the numerical 10 indicates the lower portion or base of my improved machine and 11 the upper portion thereof constituting a case within which 60 dispensing mechanism is housed, the lower portion being provided with a door 12 covering an opening through which empty magazines may be removed, and the upper portion of the case having an upper front plate 13 65 removably secured in place as by means of studs on the back face thereof engaging key hole openings 14 in the sides of the case, the lower edge of the plate 13 being secured behind a flange on a cover case 15 secured to 70 the front of the case 11, as shown in Figure 4, and the upper edge of said plate being secured by a lock of ordinary construction, as shown in Figure 1 of the drawings. A lower front plate 16 is secured to the case 75 11, the cover case being secured to this lower plate, as shown in Figure 4. Windows 17 are provided in the plate 13 through which the merchandise and indicating devices to be hereinafter described may be observed, 80 and openings 18 are provided in the plate 16 through which the merchandise may be obtained. A back cover 19 is secured to the back part of the upper portion of the main case in any suitable manner.

85 Brackets 20 are secured to the back wall 21 of the main case and to the inner face of the lower front plate 16, said brackets extending across the case from back to front and guides 22 are secured at their lower ends 90 to said brackets and rise therefrom to form receptacles in which magazines 23 containing packages 24 of merchandise are placed.

95 My improved apparatus comprises two mechanisms that are substantial duplicates of each other, so far as certain parts are concerned, both of these mechanisms being appurtenant to each stack of magazines in the case, one of these mechanisms appurtenant to a stack being a delivery mechanism and the other being a dispensing mechanism, the former being located well up in the case above the openings 18 and the latter being located at said openings.

100 Said delivery mechanism comprises de- 105 tent operating shafts 25 rotatably mounted

in the plate 16 and the back wall 21 of the case, there being two of these shafts located underneath each of the receptacles comprising the guides 22, the members of each pair of shafts being spaced apart to permit passage of magazines therebetween and also to properly locate main stack supporting detents 26 in position to support the stack of magazines when the parts are in their normal positions, said detents being secured to said shafts, and each shaft supporting a set of said detents, in the construction herein shown there being three of said detents to a set. One of said detents, as shown herein that one nearest the front of the machine, has a pin engaging a slot in an extension of one of a set of stack releasing detents, 27, each of said stack releasing detents being secured to a releasing detent shaft 28, there being two of said shafts also located underneath the stack of magazines, but above the shafts 25, and spaced apart to permit passage of magazines and to properly position the detents 27 to temporarily support the stack of magazines while the bottom magazine is being released from the stack, in a manner to be hereinafter described and as shown in Figures 4, 5 and 6 of the drawings.

A detent operating arm 29 is secured to each member of each set of shafts 28, said arms projecting in opposite directions from the shafts of each of said sets and a detent operating bar 30 is pivotally attached at its opposite ends to each of the arms 29 of each pair of shafts 28, said bar being attached at opposite sides of the axes of said shafts, so that as the bar is moved longitudinally, said arms, and consequently the shafts, will be swung in opposite directions. Each bar 30 has an extension 31 provided with a lug in which a stud 32 is adjustably secured, said stud being located in the path of movement of an actuator 33. Springs 34 are attached at their opposite ends to each bar 30 and to the plate 16 as a means for returning said bar and connected parts to normal positions after they have been moved out from said positions by the actuator 33.

In their normal positions and when the parts are at rest the lower magazine of a stack rests upon the ends of the main stack supporting detents 26, as well as against the heels 35 of the detents 27, as shown in the receptacles on the right in Figures 5 and 6. When these detents are swung, as by the operation of the bars 30 to move the outer ends of the detents toward each other, the lower ends or heels thereof and the main stack supporting detents 26 will be swung apart to release the bottom magazine of the stack and said magazine will thereupon fall passing between said heels and detents, while the outer ends of the detents 27 will be moved together to receive the next magazine, which is now the bottom magazine in the stack to thereby tem-

porarily support said stack. It will be understood that in the normal positions of rest of the parts, as shown with respect to the receptacle at the right in Figures 5 and 6, the upper ends of the detents 27 are separated and that the initial movements of the actuators 33 and bars 30 move the outer ends of these detents toward each other and thereby release the bottom magazine in the stack, the outer ends of the detents being thus positioned to obstruct movement of the rest of the stack of magazines, this being effected by movement of the actuator in one direction, and upon the return of the actuator to its normal position, as under the influence of the spring 34, the detents will assume the positions shown at the right in Figures 5 and 6 of the drawings. When the bottom magazines in the stacks are released by the delivery mechanisms just described they are free to move downwardly to the vending mechanisms hereinbefore referred to located at the openings 18 through which the packages 24 may be obtained from the magazines. The delivery mechanism is located at such distance above the openings 18 as to prevent one from obtaining the contents of more than a single magazine at a time, it being obvious that the mechanisms altho not so claimed herein may be readily adapted for vending purposes, and in which coins may be employed for regulating the operation of the mechanism.

The dispensing mechanism is not only for the purpose of enabling the contents of the magazines to be obtained, but it has a material advantage in enabling the empty magazines to be disposed of within the machine, thereby avoiding any unsightly appearance by reason of a strewing of the empty magazines about the machine.

As an aid to this purpose it will be noted that the diameters of the openings 18 are less than those of the magazines, and that the magazines when resting on the detents will have their ends in contact with the back faces of the rings bounding said openings, so that the packages 24 may be readily removed from the magazines without removing the latter from the case.

As hereinbefore mentioned these dispensing mechanisms are duplicates of the delivery mechanisms above described, and each of which dispensing mechanisms comprises detent operating shafts 36 rotatably mounted and disposed as in the delivery mechanism and having magazine supporting detents 37 secured thereto, one of said detents having a pin engaging a slot in an extension of one of a set of magazine releasing detents 38 secured to a releasing detent supporting shaft 39. Detent operating arms 40-41 are secured to project in opposite directions from the rear ends of the shafts 39 back of the back wall 21 of the case, these arms being connected by a detent operating bar 42 pivotally attached at

its opposite ends to said arms on opposite sides of the axes of the members of the pair of shafts in the manner as hereinbefore mentioned with respect to the detent operating bars of the delivery mechanism. These bars 42 have springs 43 as a means for moving them in one direction.

The delivery and dispensing mechanisms are connected to be simultaneously operated, 10 one by means of the other, in the construction herein shown the dispensing mechanism being operated from the delivery mechanism and by mechanism comprising a finger 44 on each of the arms 41 that rests in contact with 15 one end of a connecting lever 45 pivotally mounted intermediate its end on the back face of the back wall 21 of the case, and as shown in Figure 4 of the drawings, it being noted that the detent operating arms 41 are located 20 on those ends of the shafts 39 that, as above mentioned, project through said back wall 21, in the illustration in Figure 7 said levers and other pivotally mounted parts being without support, this being merely for the purpose of 25 illustration. The upper ends of the levers 45 are each in contact with one end of a dispensing mechanism actuating lever 46 secured to that end of a releasing detent shaft 28 that projects through the back wall 21 and as 30 shown in Figure 4 of the drawings.

A retarder supporting plate 47 is mounted at its upper and lower ends respectively by the brackets 20 and by brackets 48, the latter also being secured to and extending between 35 the wall 21 and plate 16. These plates support retarders 49 projecting therefrom, and said plates also serving as a dividing wall between adjacent passages for the magazines in their movements from the delivery to the dispensing mechanism. Retarders are provided 40 extending in staggered relation from opposite sides of said passages, and as shown in Figure 6 of the drawings, said retarders being for the purpose of lessening the speed of the 45 magazines in dropping from the delivery to the dispensing mechanisms and also for preventing said magazines from dropping directly into the spaces between the detents 38 and onto the detents 37, at which point they 50 might become wedged were they allowed to drop freely after release by the delivery mechanism.

If desired means may be employed for 55 registering the number of magazines that are operated upon by the machine, as shown herein comprising a counter-operating bar 50 supported on levers 51 pivotally attached to the wall 21 and having fingers engaged by the ends of the levers 46, one of the levers 51 60 being a bell crank lever, as shown in Figure 7, having one arm connected by a rod 52 with a counter 53, as shown in Figure 3.

Actuating mechanism for the apparatus hereinbefore described comprises the actuator 65 33 hereinbefore referred to that is pivotally

mounted at one end on the inner face of the front wall of the case 15, this lever having a flange 54 to engage with the stud 32 as hereinbefore mentioned. An actuating disc 55 is secured to the inner end of an actuating shaft 70 56 rotatably mounted in and projecting through the front wall of the case 15, a knob 57 being secured to said shaft outside of the case as a means for turning the shaft. The disc 55 and actuator 33 are cooperatively 75 mounted and are adapted to be operatively connected as by means of connector that may be of various forms. As hereinbefore mentioned, in some cases the machine may be arranged as a vending machine in which coins 80 will be employed for controlling actuation of the mechanism, and in such case the connector will be a coin inserted between the curved edge of the actuator and the edge of the disc and by means of which coin the actuator will be forced against the stud 32, the coin finally being released from between the actuator and disc. When the machine is adapted for use as a dispensing machine, and as herein shown and claimed, this actuator may be in 85 the form of a lobe 58 on the edge of the disc 55 and adapted to make contact with the edge of the actuator in the same manner that the coin would operate.

As hereinbefore mentioned the actuator is 90 under the influence of a spring 34, but it is desired that the movement of the actuator may be delayed as to the time of beginning its backward movement after having been moved forward by rotation of the disc 55, as 95 in a quick turning movement of the knob 57 and consequent quick release of the actuator imperfect operation of the mechanism is liable to result. Therefore, to prevent such results I provide a check 59 in the form of a frame pivotally mounted on the inner surface 100 of the front wall of the case 15 and having a retarding finger 60 and a releasing finger 61, the frame being forced toward the disc 55 and actuator 33 as by means of a spring 105 or springs 62. A releasing cam 63 is secured to the shaft 56 and has a portion adapted to engage a finger 61 to swing the frame or check 59 on its pivots.

In operation, when the parts are in their 110 normal conditions the fingers 60 will rest in contact with the face of the actuator 33. As the latter is swung to one side, in the operation of the mechanism, said finger will move from the face of the actuator into the space 115 between the edges of the actuator and disc 55, the releasing finger 61 at this time being in the space between the raised portions of the cam surfaces on the cam 63. As the rotation of the shaft 56 is completed the cam 63 120 will engage the finger 61 and swing the frame or catch 59 on its pivot against the force of the springs 62, thereby disengaging the fingers 60 from the actuator and allowing the latter to return to its normal position of rest, 125 130

this movement of the actuator thus taking place at some time after it has been disengaged from the connector. The parts are so arranged that a complete rotation of the 5 knob 57 is required to effect a complete dispensing operation of the mechanism.

In order that it may be determined before attempting to operate the machine whether or not a magazine receptacle is empty an 10 indicator is employed, it being noted that when there are more than one magazines in a receptacle this fact may be noted by observation through the windows 17. When, however, there is a single magazine in a receptacle it will be located below the window and therefore cannot be seen. Therefore, an 15 indicator 64 is placed upon the top of a stack of magazines, this being in the form of a block slidably mounted between the guides 22 and 20 having an announcer 65 rotatably mounted thereon and having on one face thereof words as Try this one to denote a magazine in the receptacle, and another face thereof a word as Empty to denote that the receptacle is 25 empty. The announcer is urged to rotate as by means of a spring properly disposed, and a latch 66 engaging a lip 67 on the announcer holds the latter against turning movement on the block, but when the block settles onto 30 the detents 38, after the last magazine has been dropped therefrom, the tail of the latch will encounter the bracket 20 and thereby disengage the latch from the lip 67 and permit the announcer to turn, thereby causing the 35 words Try this one to disappear and the word Empty to appear.

It will be noted that the indicator in this lowermost position so rests between the detents 27, as shown at the right in Fig. 10, that 40 said detents cannot be moved toward each other, and as they have been moved apart to their limit the mechanism is locked and cannot be operated until the indicator is raised.

An important feature of my invention 45 resides in that construction whereby the delivering mechanism cannot be operated from the dispensing mechanism, so that a delivery of merchandise cannot be obtained by unwaranted manipulation of the dispensing mechanism. All operations of the dispensing mechanism are effected by means of the delivery mechanism, and therefore, if an attempt be made to move either of the bars 42 to the left, as seen in Fig. 7, stops preventing 50 movement of the levers 46 will secure the result so far as movement of the bar in this direction is concerned, and if said bars be moved to the right the arms 41 will move away from the levers 45 without effect there- 55 on.

It may also be noted that the counter-operating mechanism is so arranged that a single counter is operated by each movement of each of a plurality of counter-operating 60 mechanisms, this being effected by so con-

structing the counter-operating bar 50 that it will be moved only by that lever 46 appurtenant to the mechanism being operated for dispensing purposes.

A very important feature of the invention 70 resides in the construction and arrangement of the releasing detents 27. It will be noted, as shown in Fig. 6, that the detents at the left so engage the stack of magazines that a line drawn through the axis of the pivots 75 of the detents and their points of contact at the ends thereof with the magazines, passes on that side of the center of the detents which will cause the weight of the stack to swing the outer ends of the detents toward each other. The springs 34 have power enough simply to move the outer ends of the detents 27 toward each other and therefore only such power is required to turn the knobs 57 as will overcome the tension of the springs and 80 the slight friction between the magazines and the ends of the detents, and as soon as the detents have been moved apart slightly, the weight of the stack will aid in completing the movement and thus lessen the power required to be exerted on the knobs. The second magazine in the stack is retained in the position shown at the right in Fig. 6 in which position the ends of the detents may pass freely under the magazine without touching it, 85 this referring to the magazine next to the bottom of the stack. As soon as the detents have been moved to release the bottom magazine in the stack the balance of said stack will settle onto the ends of the detents 27 and 90 as shown at the left in Fig. 6 of the drawings.

The detents 26 are provided for the purpose of supporting the whole weight of the stack of magazines and therefore remove such 105 weight from the detents 27, leaving the latter free to move unimpeded by such weight.

Wherever in the foregoing description reference is made to a single mechanism, it will be understood that the description applies 110 equally to the mechanism appurtenant to each of the receptacles for the merchandise.

It will be noted that the capacity of the lower portion 10 of the case is greater than that of the upper part 11 thereof, the purpose 115 of this being to enable the base to receive all of the containers which may have been deposited in the upper part, as the magazines being larger than the contents, the capacity of the base is increased to accommodate them. Moreover the magazines are liable to take up more room in the base than in the upper portion of the case for the reason that they will not be deposited in the orderly manner in the 120 base in which they are arranged in the upper portion of the case.

In accordance with the provisions of the patent statutes I have described the principles of operation of my invention, together 130 with the apparatus which I now consider to

represent the best embodiment thereof, but I desire to have it understood that the apparatus shown is only illustrative and that the invention may be carried out by other means and applied to uses other than those above set out.

I claim—

1. A dispensing machine comprising a case having an opening for access to merchandise within the case, means for delivering loaded magazines to a location accessible through said opening, means for independently delaying movement of magazines in a position adjacent to said location, and means for discharging empty magazines from said location.

2. A dispensing machine comprising a case having an opening for access to merchandise within the case, means for delivering loaded magazines by a series of movements to a location accessible through said opening, means for discharging empty magazines from said location by one of said movements and simultaneously therewith for temporarily obstructing delivery of the next loaded magazine in a position removed from said location.

3. A dispensing machine comprising a case having an opening for access to merchandise within the case, a set of shafts spaced apart adjacent to said opening, a detent secured to each of said shafts to receive magazines between them, and means for rocking said shafts to separate the ends of said detents for the discharge of magazines and to move the opposite ends of said detents toward each other to receive magazines thereon.

4. A dispensing machine comprising a case having an opening for access to merchandise within the case, a set of shafts spaced apart adjacent to said opening, detents secured to said shafts to jointly support merchandise between them, means for rocking said shafts in opposite directions to move said detents apart, a second set of shafts spaced apart adjacent to the first set, detents secured to the second set of shafts to receive magazines thereon, and means for rocking the second set of shafts in opposite directions for the reception and for the discharge of magazines.

5. A dispensing machine comprising a case having an opening for access to merchandise within the case, a set of shafts spaced apart adjacent to said opening, a second set of shafts spaced apart adjacent to the first mentioned set of shafts, detents secured to said shafts, a connection between said sets of shafts for simultaneous operation thereof, and means for rocking one of said sets of shafts.

6. A dispensing machine including a case having an opening for access to merchandise therein, a set of shafts spaced apart adjacent to said opening, detents secured to said shafts,

a detent operating bar connected at its opposite ends to detents on both shafts and on opposite sides of the axes thereof to simultaneously move the detents in opposite directions, and means for rocking one of said shafts.

7. A dispensing machine including a case having an opening for access to merchandise within the case, a set of shafts spaced apart adjacent to said opening, detents secured to said shaft, a second set of shafts spaced apart adjacent to the first mentioned set of shafts, detents secured to the second set of shafts and having pins engaging slots in the detents on the first mentioned set of shafts, an arm projecting from one of the second set of detents, a detent operating bar attached at its opposite ends to a detent on one of the sets of shafts and to said arm, and means for rocking one of said shafts to swing the detents on each set of shafts in opposite directions.

8. A dispensing machine including a case having an opening for access to merchandise within the case, a set of shafts spaced apart adjacent to said opening, detents secured to said shafts, a second set of shafts spaced apart adjacent to the first mentioned set of shafts, detents secured to the second set of shafts and having pins engaging slots in the detents of the first set of shafts, a detent operating bar connected at its opposite ends to detents on both shafts and on opposite sides of the axes thereof to simultaneously move the detents in opposite directions and means for rocking one of said shafts.

9. A dispensing machine including a case having an opening for access to merchandise therein, a set of shafts spaced apart adjacent to said opening, detents secured to said shafts to jointly support an article of merchandise, a detent operating bar operatively connected at its opposite ends with each of said detents to rock them in opposite directions, and means for rocking one of said shafts.

10. A dispensing machine including a case having an opening for access to merchandise therein, a set of shafts spaced apart adjacent to said opening, detents secured to said shafts, operating arms secured to said shafts and projecting in opposite directions therefrom, a detent operating bar secured to the ends of each of said arms, and means for rocking one of said shafts.

11. A dispensing machine comprising a case having an opening for access to merchandise within the case, means for delivering loaded magazines, a set of shafts spaced apart, detents secured to said shafts and spaced apart to receive and jointly support said magazines opposite said opening, the ends of said detents being movable into position to receive and temporarily support said magazines, detents secured to said shafts to

support magazines between the first mentioned detents, and means for rocking said shafts.

12. A dispensing machine comprising a case having an opening for access to merchandise within the case, a set of shafts adjacent to said opening, detents secured to said shafts, and spaced apart, means for rocking said shafts to locate each of said detents to jointly receive a magazine on the end thereof, then to receive said magazine between them, and then to discharge said magazine, and means for delivering magazines to said detents.

13. A dispensing machine comprising a case having an opening for access to merchandise within the case, a set of shafts adjacent to said opening, detents secured to said shafts and spaced apart, means for rocking said shafts first in one direction to move said detents to jointly receive a magazine on their ends, then in another direction to jointly receive and support said magazine between them, and then in an opposite direction to discharge said magazine, and means for delivering magazines to said detents.

14. A dispensing machine comprising a case having an opening for access to merchandise within the case, a set of shafts located adjacent to said magazines, detents secured to said shafts, a second set of shafts operatively connected with the first mentioned set of shafts, detents secured to the second set of shafts, and means for rocking the first set of shafts to swing detents thereon first in one direction to receive a loaded magazine thereon, then in an opposite direction to deliver said magazine to the detents on the second set of shafts, and then in an opposite direction to discharge said magazines, and means for delivering magazines to the detents on the first mentioned set of shafts.

15. A dispensing machine including dispensing mechanism, an actuator operatively connected therewith, an actuating disc adapted to be connected with said actuator by a connector, means for delaying returning movement of said actuator, and means for rotating said disc to operate said actuator.

16. A dispensing machine including dispensing mechanism, an actuator operatively connected therewith, an actuating disc adapted to be connected with said actuator by a connector, a check swingingly mounted to obstruct movement of said connector in one direction, means for operating said check to release said actuator, and means for rotating said disc to operate said actuator.

17. A dispensing machine including a dispensing mechanism, an actuator operatively connected therewith, an actuating disc adapted to be connected with said actuator by a connector, a check having a releasing finger and a retarding finger, the latter to engage said actuator, means for actuating said disc,

and means to engage said releasing finger to operate said check.

18. A dispensing machine including a dispensing mechanism, an actuator operatively connected therewith, an actuating disc adapted to be connected with said actuator by a connector, a cam secured to rotate with said actuating disc, a pivotally mounted check having a releasing and a retarding finger, the latter to engage said actuator to check its movement, said releasing finger being engaged by said cam, and means for actuating said disc and cam.

19. A dispensing machine including a dispensing mechanism, the latter including a rocking shaft, a member operatively connected with said shaft, an actuator mounted to make contact with said member to operate said shaft, an actuating disc adapted to be connected with said actuator by a connector, a check mounted to obstruct movement of said actuator in one direction, means for operating said check to release said actuator, and means for operating said actuator.

20. A dispensing machine including means for controlling movement of a stack of merchandise, an indicator adapted to ride on said stack, an announcer operatively movably mounted on said indicator, and means for operating said announcer by reason of movement of said indicator.

21. A dispensing machine including means for controlling movement of a stack of merchandise, an indicator adapted to ride on said stack, an announcer pivotally mounted on said indicator to present different sides to view, means for moving said announcer, and means for releasing said announcer for movement.

22. A dispensing machine including means for controlling movement of a stack of merchandise, an indicator adapted to ride on said stack, means movably mounted on said indicator for denoting the amount of merchandise within the receptacle, and means for causing the indicator to lock the mechanism in the final position of said indicator.

23. A dispensing machine including means for controlling movement of a stack of merchandise, and embodying movably mounted detents adapted to swing apart, and an indicator adapted to ride on said stack and be positioned between the detents to lock them against movement when the indicator is in its final position.

24. A dispensing machine including means for controlling movement of a stack of merchandise, and unitary means for simultaneously locking said controlling means, together with means movably mounted thereon for visually indicating exhaustion of said merchandise.

25. A dispensing machine including a case having an opening for access to merchandise therein, interconnected means simultaneously

- operatable for retaining a stack of receptacles for merchandise at a distance remote from said opening, for releasing said stack and for retaining it in a lowered position, and for separation therefrom and for movement independently thereof for releasing the bottom article in the stack for delivery at said opening.
26. A dispensing machine including a case having an opening for access to merchandise therein, interconnected means simultaneously operatable for retaining the stack of merchandise at a distance remote from said opening, for releasing the bottom article in the stack, for receiving and supporting said ar-
- ticle above said opening and separated from the stack, and for releasing said article for delivery at said opening.
27. A dispensing machine including a case having an opening for access to merchandise therein, interconnected means simultaneously operatable for retaining a stack of merchandise at a distance remote from said opening, for releasing said stack for falling movement, for stopping the movement of said stack, for releasing the bottom article in the stack, for stopping the movement of said article at a point above said opening, and for releasing said article for delivery at said opening.

PENROSE R. HOOPES.
